DESIGN FOR A COMBINATION COMB HOLDER AND BRUSH

Mary Anna North, New York, N. Y., assignor to Celluloid Corporation, a corporation of New Jersey

Application February 23, 1939, Serial No. 83,157

Term of patent 14 years

To all whom it may concern:

Be it known that I, Mary A. North, a citizen of the United States, residing at New York, county of New York, State of New York, have invented a new, original, and ornamental Design for a Combination Comb Holder and Brush, of which the following is a specification, reference being had to the accompanying drawing, forming part thereof.

In the accompanying drawing:

tion comb holder and brush embodying my new design;

I claim:

The ornamental design for a combination comb holder and brush, substantially as shown.

MARY ANNA NORTH.
